UNITED STATES PATENT OFFICE

137,738

DESIGN FOR A SHINGLE ROOF PATCHING TOOL

Roy C. Bradley, Aguanga, Calif.

Application January 3, 1944, Serial No. 112,153

Term of patent 14 years

(Cl. D93—4)

To all whom it may concern:

Be it known that I, Roy C. Bradley, a citizen of the United States, residing at Aguanga, in the county of Riverside and State of California, have invented a new, original, and ornamental Design for a Shingle Roof Patching Tool, of which the following is a specification, reference being had to the accompanying drawing, forming part thereof.

Figure 1 is a side elevational view of a shingle roof patching tool showing my new design,
Figure 2 is a bottom plan view, and
Figure 3 is an end elevational view.

I claim:

The ornamental design for a shingle roof patching tool, as shown.

ROY C. BRADLEY.
